UNITED STATES PATENT OFFICE.

WARREN BARNHART, OF CHICAGO, ILLINOIS, ASSIGNOR TO ARTHUR M. BARNHART AND ALSON E. BARNHART, OF SAME PLACE.

DESIGN FOR A FONT OF PRINTING-TYPE.

SPECIFICATION forming part of Design No. 17,701, dated September 13, 1887.

Application filed February 1, 1887. Serial No. 236,105. Term of patent 7 years.

To all whom it may concern:

Be it known that I, WARREN BARNHART, a citizen of the United States, residing in the city of Chicago, county of Cook, and State of Illinois, have invented and produced a new and original Design for a Font of Printing-Types, of which the following is a specification, reference being had to the accompanying typographical illustration, forming a part hereof.

10 The general character of the design is semi-ornamental condensed light-face, the vertical, inclined, and curved strokes being of uniform weight; and it consists of capitals, figures, points, dollar-mark, and character &.

15 The special features are the filling in or shading at the top and bottom of all the letters, and the especially novel construction of A, B, E, F, H, P, R. The cross-stroke on A extends beyond the inclined lines of the letter, and is finished at the ends by the use of triangular-shaped points. In B the end of the central horizontal line terminates in a sharp point which runs diagonally across the upright stroke of the letter, as also does the lower end of the

20 loops in letters P and R. The cross-stroke in H has a similar appendage, as have the central strokes of E and F. This appendage is distinguishable from a mere ceriph, which it some-

what resembles, by the position in which it is placed, being one where a ceriph is not usually employed, and by the further fact that, although its form is substantially an isosceles triangle, it is not placed symmetrically with respect to the line to which it pertains, being joined thereto not at the angle between its equal sides, but at 35 one of the angles between unequal sides, and having all its sides oblique to the line and the angle between its equal sides, which is the terminal angle, very acute. The lower left-hand part or bowl of character & is composed of 40 one curved stroke and two straight ones meeting nearly at right angles.

I claim—

The design for a font of printing-types the general character of which is semi-ornamental 45 light-face condensed, and having as special features the triangular-shaped points which terminate horizontal strokes at the middle of the letter, and are placed unsymmetrically with respect to such strokes, having all their sides 50 oblique thereto and their terminal angles very acute, substantially as illustrated.

WARREN BARNHART.
